US00D437708S

(12) **United States Design Patent** (10) Patent No.: **US D437,708 S**
Bargmann et al. (45) Date of Patent: ** Feb. 20, 2001

(54) **FURNITURE UNIT**

(75) Inventors: **Jay D. Bargmann**, Pelham, NY (US);
Hubert L. Ostertag, Holland, MI (US);
David R. Appel, Ada, MI (US);
George J. Simons, Jr., Grand Rapids,
MI (US); **Mark A. Buchalter**;
Yasuyuki Hirai, both of East Grand
Rapids, MI (US); **Howard M.**
Montgomery, Grand Rapids, MI (US)

(73) Assignee: **Steelcase Development Inc.**, Grand
Rapids, MI (US)

(**) Term: **14 Years**

(21) Appl. No.: **29/113,213**

(22) Filed: **Nov. 1, 1999**

(51) LOC (7) Cl. **06-03**

(52) U.S. Cl. **D6/399**; D6/397; D6/477;
D6/478

(74) Attorney, Agent, or Firm—Price Heneveld Cooper DeWitt & Litton

(57) **CLAIM**

We claim the ornamental design for a furniture unit, as shown and described.

DESCRIPTION

FIG. 1 is a perspective view of our furniture unit design; FIG. 2 is a left end view thereof, the right end being a mirror image of the left end view;

FIG. 3 is a front view thereof;

FIG. 4 is a top view thereof;

FIG. 5 is a rear view thereof;

FIG. 6 is a perspective view similar to FIG. 1 but showing all worksurfaces in raised position;

FIG. 7 is a left end view of FIG. 6;

FIG. 8 is a perspective view of a second modified embodiment of our design; and,

FIG. 9 is an end view thereof.

The surface(s) or portion(s) of the article not shown in the drawing or described in the specification form(s) no part of the claimed design.

1 Claim, 6 Drawing Sheets
